CAST FIREPLACE

Gerald L. Jonas, San Francisco, Calif., assignor to Fire
Drum Corporation, San Francisco, Calif., a corporation
of California

Filed May 28, 1965, Ser. No. 85,507

Term of patent 14 years

(Cl. D81—7)

FIG. 6**FIG. 7**FIGURE 1 is a top plan view of the cast fireplace showing my new design;

FIGURE 2 is a side elevational view thereof;

FIGURE 3 is a front elevational view;

FIGURE 4 is a vertical cross-sectional view taken along the line IV—IV in FIGURE 3;

FIGURE 5 is a back elevational view;

FIGURE 6 is a perspective view of the cast fireplace, showing my new design; and

FIGURE 7 is a side elevational view showing the fitting in the wall without change of the design.

The broken line showing of a wall fragment in FIGURE 7 and the fragmentary broken line showings of a flue in FIGURES 6 and 7 are for illustrative purposes only.

I claim:

The ornamental design for the cast fireplace, as shown and described.
